2 Sheets-Sheet 2

Fig. 2.

Fig. 3.

Fig. 4.

A hand-drawn diagram of a lock mechanism. It features a rectangular frame with a central vertical slot. A horizontal pin or bolt is positioned within this slot. A circular component, possibly a keyway or a lock body, is attached to the left side of the pin. The diagram is annotated with numbers: '27' is on the top left corner of the frame; '23' is on the bottom left corner of the frame; '24' is on the bottom left side of the central slot; '25' is on the top right corner of the frame; and '14' is on the right side of the pin. The drawing is done in black ink on a white background.

UNITED STATES PATENT OFFICE.

EDWARD R. DAVIS, OF LUZERNE, AND CHARLES C. SHIBER, OF WILKES-BARRE, PENNSYLVANIA.

COMBINED WINDOW-SHADE AND CURTAIN-ROD SUPPORT.

Application filed September 18, 1928. Serial No. 306,719.

This invention relates to a combined window shade and curtain rod support, and more particularly to a device of this character which may be very readily applied to the frames of windows or doors, and which may be expeditiously and cheaply manufactured.

An important object of the invention is to provide a device of this character which may be accurately adjusted to permit its use with window shades which have been inaccurately cut or improperly measured and in which the adjustment may be made with the least possible labor on the part of the person installing the fixture.

15 A further and important object of the invention is to provide in a device of this character a structure such that the means for mounting both the shade roller and the curtain rods may be produced from a single sheet 20 of metal and at the same time will provide an efficient and convenient mounting for such fixture.

25 These and other objects we attain by the construction shown in the accompanying drawings, wherein for the purpose of illustration is shown a preferred embodiment of our invention and wherein

30 Figure 1 is a front elevation showing brackets constructed in accordance with our invention applied to a window frame;

Figures 2, 3 and 4 are sections on the lines 2-2, 3-3 and 4-4 of Figure 1;

Figure 5 is a front elevation of one of the base plates removed;

35 Figure 6 is a plan of the blank from which the sliding plate is constructed;

Figure 7 is a plan of the blank from which the base plate is constructed;

40 Figure 8 is a detail sectional view through one of the curtain rod engaging elements showing the same engaged in a curtain rod.

Referring now more particularly to the drawings, the numeral 10 generally designates what may be termed a base plate which 45 in the construction of the brackets will be provided in pairs adapted to be arranged at opposite sides of the window or door frame F to which the fixtures are being applied.

Any suitable means may be provided for securing such base plate to the frame, but the disclosed structure is preferred. This structure includes a flange 11 formed upon one end of the plate and having at its free edge an angular tang 12 adapted to underlie the plate proper and so engage in the edge 55 face of a framing element to the front face of which the base plate is applied. Adjacent its opposite end the base plate is provided with an opening through which a brad 13 may be extended to engage in the surface of 60 the frame.

Associated with each base plate is a mounting plate generally designated 14. This mounting plate is slidably mounted upon the base plate in any suitable or preferred manner.

In the present instance, the mounting plate is disclosed as provided upon its side edges with roll beads 15 which are adapted to enter channels 16 formed upon the side edges of the base plate 10 by rolling, and to frictionally fit therein. The edges of the beads 15 are preferably provided with scrolled reverts 17 to serve both as an ornamentation and as a means for excluding dust from the channels 70 16. At one end the mounting plate 14 is provided with a tongue 18 which is reverted upon the upper surface of the mounting plate and is provided intermediate its ends with a plurality of V-shaped folds 19 which project outwardly from the face of the plate. This tongue is of the same width as the distance between the opposed edge flanges 20 of a curtain rod 21 of the usual flat channelled type now in common use, and the folds 19 are accordingly able to enter these channels 75 20 to provide a support for the rod. The engagement provided is frictional and results from compression of the base of the folds as the rod is forced into position thereover. 90 This frictional grip is increased by the engagement of pressed fits 22 formed upon the outer faces of one arm of the fold.

The plate 14 is provided with a second tongue 23 which is struck out from the edge 95 of the metal and preferably has the contour

usually provided for shade brackets. This tongue 23 is provided with an opening 24 of proper type for engagement with the end of the shade roller with which it is to coact, and at the junction of the tongue with the plate an opening 25 is formed.

This opening 25 receives a reduced extremity 26 formed upon the tongue 18, and the engagement of this extremity in the opening 10 serves to prevent separation of the free end of the tongue 18 from the mounting plate. At one end the mounting plate is preferably formed with a hand grip which may be produced by bending an end edge of the plate 15 as indicated at 27.

While the frictional grip provided by the engagement of the scrolls 15 in the channels 16 of the base plate will ordinarily prove sufficient to prevent any dislodgment of the 20 mounting plate after it has once been adjusted, some additional means may be provided for securing the mounting plate in such positions. In the present instance, I have illustrated the base plate as having formed in the 25 wall of one of the channels 16, an opening 26 thru which is extended a bowed frictional spring 27 for engagement with the scroll 15 which is disposed in this channel. This friction spring tends to shift the mounting plate 30 14 transversely and thus insure engagement of the scrolls with the walls of the beads, thus increasing the frictional resistance to movement of the plate.

It will be obvious that a structure of this 35 character may be very readily and cheaply produced and will provide a most convenient and satisfactory mounting for shade rollers and curtain rods when employed in combination. It will also be obvious that the construction hereinbefore set forth is capable 40 of a certain range of change and modification without materially departing from the spirit of the invention, and we accordingly do not limit ourselves to such specific structure except as hereinafter claimed.

What we claim, is:

1. In a curtain rod bracket for flattened tubular curtain rods, a base plate having means whereby it may be secured to a window frame, a second plate slidable upon the first plate and transversely of the frame, and a tongue upon said second plate and having outstanding folds spaced transversely of the frame and each adapted to enter the open end 55 of the curtain rod.

2. In a curtain rod bracket for flattened tubular curtain rods, a base plate having means whereby it may be secured to a window frame, a second plate slidable upon the 60 first plate and transversely of the frame, and a tongue upon the second plate, said tongue being reverted upon the outer face of the second plate and being provided intermediate its ends with V-shaped folds, the tongue be-

ing of a width such that it may enter between 65 the edge flanges of a curtain rod.

3. In a curtain rod bracket for flattened tubular curtain rods, a base plate having means whereby it may be secured to a window frame, a second plate slidable upon the first 70 plate transversely of the window frame, and a plurality of V-shaped folds projecting outwardly from the face of the second plate and spaced from one another transversely of the window frame, said folds having connections 75 with the second plate permitting contraction of the arms thereof and being of resilient material.

4. In a curtain rod bracket for flattened tubular curtain rods, a base plate having 80 means whereby it may be secured to a window frame, a second plate slidable upon the first plate transversely of the window frame, a plurality of V-shaped folds projecting outwardly from the face of the second plate and 85 spaced from one another transversely of the window frame, said folds having connections with the second plate permitting contraction of the arms thereof and being of resilient material, and a second tongue projecting outwardly from said second plate and apertured for the reception of the fixture upon one end of the shade roller, said first and second tongues having engagement with one another preventing separation of the free end of the 90 first tongue from the second plate.

5. In a curtain rod bracket for flattened tubular curtain rods, a base plate having means whereby it may be secured to a window frame, a second plate slidable upon the first 100 plate transversely of the frame, and a tongue upon said second plate having outstanding folds spaced transversely of the frame and each adapted to enter the open end of the curtain rod, the edges of the first and second 105 plates having portions frictionally engaging with one another to maintain the plates in adjusted positions.

6. In a curtain rod bracket for flattened tubular curtain rods, a base plate having 110 means whereby it may be secured to a window frame, a second plate slidable upon the first plate transversely of the frame, and a tongue upon said second plate having outstanding folds spaced transversely of the 115 frame and each adapted to enter the open end of the curtain rod, the edges of the second plate having roll beads, the edges of the first plate having channels receiving and fitting the beads of the second plate and frictionally engaging therewith.

7. In a curtain rod bracket for flattened tubular curtain rods, a base plate having means whereby it may be secured to a window frame, a second plate slidable upon the first 120 plate transversely of the frame, a tongue upon said second plate having outstanding folds spaced transversely of the frame and

each adapted to enter the open end of the curtain rod, the edges of the second plate having roll beads, the edges of the first plate having channels receiving and fitting the beads of the second plate and frictionally engaging therewith, the wall of one of said channels being apertured, and a friction spring extending through said aperture to engage the bead of the second plate which is disposed therein. ¹⁰

In testimony whereof we hereunto affix our signatures.

EDWARD R. DAVIS.

CHARLES C. SHIBER.
